United States Patent Office

Des. 188,998
Patented Oct. 11, 1960

188,998

PLIERS

Robert H. Elfsten, Los Angeles, Calif., assignor to
Bestools, Inc., Lynwood, Calif., a corporation of California

Filed July 6, 1959, Ser. No. 56,661

Term of patent 14 years

(Cl. D54—13)

FIG. 1.

FIG. 2.

FIG. 3.

FIG. 4.

Fig. 1 is a perspective view of pliers embodying my new design;

Fig. 2 is a side elevational view thereof;

Fig. 3 is a bottom plan view of the pliers; and
Fig. 4 is an end elevational view thereof.

I claim:

The ornamental design for pliers, as shown.
